(57) **CLAIM**

The ornamental design for a pull tab of a slide fastener slider, as shown and described.

DESCRIPTION

FIG. 1 is a front elevational view of a pull tab of a slide fastener slider of the claimed design, the rear elevational view is identical to the front elevational view;

FIG. 2 is a top view of the design of FIG. 1;

FIG. 3 is a bottom view of the design of FIG. 1;

FIG. 4 is a right side view of the design of FIG. 1, the left side view is identical to the right side view; and,
FIG. 5 is a cross-sectional view of the design of FIG. 1, taken on section lines 5—5 of FIG. 1.
